THREAD SEVERING DEVICE FOR SEWING MACHINES

Thomas A. Anderson, Hartwell, Ga., assignor, by mesne assignments, to The Singer Manufacturing Company, Elizabeth, N. J., a corporation of New Jersey

Application December 9, 1939, Serial No. 308,465

30 Claims. (Cl. 112—252)

This invention relates to thread severing means and more particularly to thread severing means associated with and forming a part of a sewing machine.

In the manufacture of garments, the closing of bags, and in many other instances where articles are stitched one after another it is the practice to pass the articles through a sewing machine operating at a high rate of speed practically as fast as they can be fed to the sewing machine by the operation, without stopping or slowing down the speed of operation of the sewing machine during the interval between the final stitching operation on one article and the initial stitching operation on the succeeding article, with the result that the successive articles are connected by a thread chain or a series of thread loops which have to be cut. The cutting of the threads connecting such articles ordinarily is done by the operator with a pair of scissors, even though such a method of severing the threads between the articles is not satisfactory as it necessitates a separate operation requiring an appreciable amount of the operator's time, and, as only one cut between articles is made, it leaves a "tail" of thread attached to each end of the article.

It has been proposed to equip sewing machines with attachments which would sever the thread after the stitching operation on each article, but such attachments have not proven entirely satisfactory due to the fact that they have required some operation on the part of the operator, were complicated, required modification of the sewing machine, or left a relatively long "tail" of threads attached to each end of the article which was stitched.

In my copending application for "Thread severing device for sewing machines" filed May 9, 1939, Serial No. 272,669, I have shown and described a thread severing means for sewing machines which is not open to the above objections to prior thread severing means for sewing machines in that the thread is severed automatically and immediately after the last stitch upon the article. Furthermore, succeeding thread loops or the thread chain formed by the continued operation of the sewing machine are destroyed until just prior to the introduction of a succeeding article into a position to be stitched, thereby eliminating not only the thread "tail" from both ends of the articles, but also the necessity of the operator to cut the thread between successive articles, and leaving her free to devote her entire time to feeding articles into stitching position.

In accordance with my aforesaid invention the 55

sewing machine is provided with cooperating severing elements which are maintained inoperative as long as the article to be stitched is between them, but which are brought into operation to sever the thread immediately upon the passage of the article from between them, thereby making the severing operation entirely independent of the operator, or of the duration of the stitching operation, and insuring the severing of the thread close to the stitched article. The cooperating severing elements continue to operate as long as the machine is operating and there is no stitched article between them so that the thread chain or thread loops which are formed between articles are continuously destroyed until a succeeding article enters between the severing elements, when they again are rendered inoperative.

Contrary to previously proposed means for severing the thread after the completion of the stitching operation on any article by shearing the thread, my aforesaid invention provides for severing the thread by crushing it between cooperating severing elements, at least one of which is mounted to move toward the other with sufficient force to cause the thread to be given a blow which will sever it. One of the cooperating severing elements is in the form of a pressure or anvil member and the other cooperating severing element is in the form of a hammer member and may have a sharp edge. The anvil member preferably is carried by the presser foot of the sewing machine and the hammer member preferably is carried by and forms a part of the feed dog of the sewing machine. Thus, as long as a stitched article is passing beneath the pressure or anvil member the latter will be raised to a position where it will not be struck by the hammer member of the feed dog, and the cooperating anvil and hammer members will be maintained inoperative, but as soon as the stitching operation on the article has been completed and it has passed from beneath the pressure or anvil member, the latter will be forced down into a position where it can be struck by the hammer member during the normal cycle of movement of the feed dog, and as the thread will be between the anvil and hammer during such movement it will be crushed and severed at the stitch just behind the last stitch on the article due to the fact that the feed dog of a sewing machine operates in synchronism with the needle. As the feed dog continues to operate as long as the sewing machine remains in operation, the sharp edged hammer member carried thereby con-

tinues to strike against the anvil as long as there is no stitched article between them with the result that the entire length of thread between stitched articles is literally masticated or chewed away.

The present invention is an improvement on the form of thread severing means shown and described in my aforesaid application, Serial No. 272,669 in that the pressure member, which also preferably is carried by the presser foot, is provided on its lower face with an upwardly-extending recess or depression having a sharp lower edge with which the severing element on the feed dog cooperates so that the enchain loops attached to a stitched article are severed by a shearing action as the severing means on the feed dog wipes across the lower surface of the pressure member. As in my aforesaid device the pressure member is resiliently urged towards the feed dog so that it may maintain contact with the severing element carried by the feed dog for an appreciable period of time during the movement of the latter.

The invention will be further described in connection with the accompanying drawing but it is to be understood that such further illustration and description is by way of exemplification and that the invention is not limited thereto except to the extent set forth in the appended claims.

In the drawing:

Fig. 1 is a vertical sectional view through a portion of a sewing machine having the present thread severing means secured thereto.

Fig. 2 is a horizontal sectional view on line 2—2 of Fig. 1.

Fig. 3 is a horizontal sectional view on line 3—3 of Fig. 1.

Fig. 4 is an enlarged vertical sectional view through the cooperating severing elements, showing the pressure member carried by the presser foot in its lower or severing position.

Fig. 5 is a perspective view of the upper severing member.

Fig. 6 is a bottom plan view of a modified form of upper severing member, and

Fig. 7 is a bottom plan view of a further modification of the upper severing member.

The present invention may be applied to lock-stitch sewing machines, chain-stitch sewing machines, over-edgers, two needle sewing machines, or any other type of sewing machine where the articles to be stitched are passed successively through the stitching position, whether such machines are of the rotary shuttle or reciprocating shuttle type.

For purpose of illustration, the invention is shown in the accompanying drawing as applied to a plain lock-stitch sewing machine having the usual head 1 which carries a presser bar 2. Detachably secured to the presser bar 2, by a screw 3, is a presser-foot 4 which is apertured to provide clearance for the usual vertically reciprocating and eye-pointed needle 5. The presser foot is shown as being rigid, but in some instances it may be desired to use a presser foot having the bottom part thereof hinged. The sewing machine also has the usual work-supporting bed-plate 6 provided with a throat plate 7 having an opening 8 for the needle and a slot 9 for the feeding teeth of a feed dog 10. The usual mechanism, a part of which is shown at 11, is provided to impart the back and forth and up and down movements to the feed dog to feed the articles to be stitched through the sewing machine in the direction indicated by the arrow in Fig. 1 of the drawing.

An upper severing member 12 is positioned immediately behind the presser foot and has a pair of forwardly-extending arms 13 straddling the presser foot and pivotally connected thereto at 14.

5 The severing member 12 has a recess 15 in its upper side for receiving one end of a coiled bow spring 16 which constantly urges the severing member downwardly. The upper end 17 of the spring 16 loosely encircles the presser bar 2 beneath a shoulder just above where the clamp screw 3 secures the presser foot thereto.

The upper severing member 12 has a round, vertical bore b extending therethrough. The bore b is filled for the greater part of its length with a plug of brass, or some other relatively soft material 22, such as solder or leather, adjustably secured in spaced relation from the bottom face of the member by a set screw s or the like, to form a recess 18 in the lower face of said member. The plug 22 is likewise spaced a suitable distance from the upper face of the severing member 12 to provide the recess 15 for receiving the lower end of the bow spring 16. The lower end of the bore b forms a sharp edge with the lower face of the severing member 12 to provide, at the rear side of the bore, a shearing edge 19 for cooperation with a lower severing member 20, preferably formed as a tooth on the feed dog 10, rearwardly of the usual feeding teeth of the feed dog. The lower severing member 20 preferably has a flat upper surface and a transversely-extending rear cutting edge 21 adapted to cooperate with the cutting edge 19 of the upper severing member 12.

35 The upper severing member 12 and the feed dog 10 are of tool steel, or of one of the many special steels now available, or a soft, low-carbon steel case hardened, in order to reduce wear and to maintain the shearing edges 19 and 21 sharp at all times. The lower severing member 20 is 40 of the shape shown in Fig. 4. By so shaping the lower severing member ample thickness is provided should rehoning eventually become necessary.

45 The presser foot 3 is formed with the usual upwardly-curved split toe portion under which the articles to be stitched are fed, and through which the needle passes. In order to provide a more extended surface to grip the lower thread 50 and prevent it from being pulled back into the sewing machine, the bottom thereof is made longer than usual.

The feed dog 10 is similar to a feed dog now used on a well known type sewing machine except that it is made of tool steel and has additional feeding teeth and the severing member 20 at the rear thereof.

In the modified form of the upper severing member 12', shown in Fig. 6, the recess 18' is of generally oval shape and extends straight across the lower face of the severing member. When the recess is of substantial length and extends straight across the lower face of the upper severing member it should be of less width than the cooperating severing member carried by the feed dog to prevent possibility of the cutting edge of the latter extending up into and being caught in the recess.

The upper severing member 12' shown in Fig. 7 has an elongated recess 18' extending diagonally across the lower face thereof. While such a recess has been found to be satisfactory, a round recess, such as is shown in Fig. 5, or an oval recess, as shown in Fig. 6, is preferred.

As long as an article is being stitched it will

lie between the upper severing member 12 and the lower severing member 20 and maintain them inoperative. However, as soon as the stitching of an article has been completed and the article has passed from between the members 12 and 20, as shown in Fig. 4, the spring 16 forces the upper severing member 12 downwardly so that it is in a position to coact with the lower member 20 as the feed dog approaches the end of its next upper rearward movement. As the feed dog moves rearwardly in its next cycle of movement the sharp edge 21 of the tooth 20 strikes against the lower face of the upper member 12, and a further rearward movement of the feed dog will cause the edge 21 to wipe across the lower face of the member 12 until the portion thereof which lies underneath the thread attached to the article reaches the sharp rear edge 19 of the recess 18, Fig. 4, when the thread will be severed with a clean cut. In actual operation it has been found that as the thread attached to a stitched article passes beneath the recess in the upper severing member it bows upwardly into the recess and is cut off before it can get out, and thereby facilitates a clean severing action as the sharp edge 21 of the tooth 20 wipes across the sharp edge of the recess.

As shown in Fig. 1 the lower face of the upper severing member assumes a substantially horizontal position when that member is raised by the passage of a stitched article beneath it. However, as soon as a stitched article passes from beneath the upper severing member, and that member is forced downward by the spring 16, as shown in Fig. 4, the lower face of said member is rearwardly inclined downwardly, so that as the cutting edge 21 of the lower severing member wipes across the lower face of the upper severing member, the latter will be raised slightly. The angle of inclination which the upper severing member assumes when in a position to cooperate with the lower severing member, and the raising thereof by the lower severing member as the cutting edge 21 wipes across the lower face of the upper severing member, facilitates the cutting of the thread attached to a stitched article.

As the spring 16 forces the upper severing member down into a position to cooperate with the severing edge 21 of the lower severing member as soon as a stitched article passes from between them the thread will be cut from the article close thereto and there will be no long "tail" of thread or enchain loops left hanging to the article; also, as the mechanism for operating the feed dog is synchronized with the mechanism for operating the needle, the feed dog moves through its cycle once for each stitch which the needle makes. It will therefore be apparent that the thread-chain will be severed in the work-advancing movement of the feed-dog next succeeding that in which the work is advanced beyond the member 12.

As long as the upper severing member 12 is in its lower position the sharp cutting edge 21 of the lower severing member will strike, and wipe across the lower face thereof during each cycle of movement of the feed dog. Thus, the chain of thread loops formed between the final stitch upon one article and the initial stitch on the 70 succeeding article will, by the continued operation of the sewing machine, repeatedly be subjected to the cooperating severing action of the cutting edges 19 and 21, with the result that the entire chain of thread loops will be destroyed 75

until the very instant the succeeding article is fed rearwardly far enough to pass beneath the upper severing member 12 and to raise it to its inoperative position shown in Fig. 1. Thus, the "tail" of thread is eliminated from both ends of a stitched article.

While the invention is particularly adapted for sewing machines in which successive articles to be stitched are fed through the sewing machine without stopping the sewing machine between successive articles, it is equally as well adapted to sewing machines which are not so operated and which are stopped after the sewing of each article, and in such cases will function to sever the "tail" of the thread close to the article and just after the last stitch made upon the article.

I claim:

1. In a sewing machine, a thread severing device comprising a severing member having a cutting edge positioned at one side of the path of stitched articles through the machine, a cooperating severing member having a cutting edge positioned at the opposite side of said path, said cooperating severing members being in alignment with the needle of the machine in the direction of travel of stitched articles through the machine, and means for moving one of said severing members relative to the other in the direction of movement of stitched articles through the machine and in shearing relation to the other severing member.

2. In a sewing machine, a thread severing device comprising a severing member having a cutting edge positioned at one side of the path of stitched articles through the machine, a cooperating severing member having a cutting edge positioned at the opposite side of said path, said cooperating severing members being in alignment with the needle of the machine in the direction of travel of stitched articles through the machine, means for moving one of said severing members towards the other, and means for moving one of said severing members relative to the other in the direction of movement of stitched articles through the machine and in shearing relation to the other severing member.

3. In a sewing machine, a presser foot, a severing member carried by the presser foot and provided with a cutting edge, a cooperating severing member having a cutting edge positioned at the side of the path of stitched articles through the machine opposite the presser foot, means for moving one of said severing members towards the other when a stitched article is not between them, and means for moving one of said severing members relative to the other in the direction of movement of stitched articles through the machine and in shearing relation to the other severing member.

4. In a sewing machine, a presser foot, a feed dog, a severing member carried by the presser foot and having a cutting edge, a cooperating severing member having a cutting edge and carried by the feed dog, means for moving one of said severing members towards the other when a stitched article is not between them, and means for moving one of said severing members relative to the other in the direction of movement of stitched articles through the machine and in shearing relation to the other severing member.

5. In a sewing machine, a presser foot, a severing member carried by the presser foot and having a cutting edge, a cooperating severing member having a cutting edge positioned at the side of the path of stitched articles through the ma-

chine opposite the presser foot, means for resiliently urging the severing member carried by the presser foot towards the cooperating severing member, and means for moving the cooperating severing member relative to the severing member carried by the presser foot in the direction of movement of stitched articles through the machine and in shearing relation to the severing member carried by the presser foot.

6. In a sewing machine, a presser foot, a severing member carried by the presser foot and having a cutting edge, a cooperating severing member having a cutting edge positioned at the side of the path of stitched articles through the machine opposite the presser foot, means for moving the severing member carried by the presser foot towards the cooperating severing member when a stitched article is not between said severing members, and means for moving the cooperating severing member relative to the severing member carried by the presser foot in the direction of movement of stitched articles through the machine and in shearing relation to the severing member carried by the presser foot.

7. In a sewing machine, a feed dog, a severing member having a cutting edge positioned at the side of the path of stitched articles through the machine opposite the feed dog, a cooperating severing member having a cutting edge and carried by the feed dog, means for resiliently urging said first-mentioned severing member towards said cooperating severing member, and means for moving said cooperating severing member relative to said first-mentioned severing member in the direction of movement of stitched articles through the machine and in shearing relation to said first-mentioned severing member.

8. In a sewing machine, a feed dog, a severing member having a cutting edge positioned at the side of the path of stitched articles through the machine opposite the feed dog, a cooperating severing member having a cutting edge and carried by the feed dog, means for moving said first-mentioned severing member towards said cooperating severing member when a stitched article is not between said severing members, and means for moving said cooperating severing member relative to said first-mentioned severing member in the direction of movement of stitched articles through the machine and in shearing relation to said first-mentioned severing member.

9. In a sewing machine, a presser foot, a feed dog, a severing member carried by the presser foot and having a cutting edge, a cooperating severing member having a cutting edge and carried by the feed dog, means for resiliently urging the severing member carried by the presser foot towards the cooperating severing member, and means for moving the cooperating severing member relative to the severing member carried by the presser foot in the direction of movement of stitched articles through the machine and in shearing relation to the severing member carried by the presser foot.

10. In a sewing machine, a presser foot, a feed dog, a severing member carried by the presser foot and having a cutting edge, a cooperating severing member having a cutting edge and carried by the feed dog, means for moving the severing member carried by the presser foot towards the cooperating severing member when a stitched article is not between said severing members, and means for moving the cooperating severing member relative to the severing mem-

ber carried by the presser foot in the direction of movement of stitched articles through the machine and in shearing relation to the severing member carried by the presser foot.

5 11. A thread severing device for a sewing machine comprising a severing member adapted to be positioned at one side of the path of stitched articles through the machine, a cooperating severing member adapted to be positioned at the

10 opposite side of said path, one of said severing members having a face opposite the other of said severing members, said face having a recess therein, the rear edge of said recess forming a sharp shearing edge with said face, and means for causing the other of said severing members to move across said sharp edge in shearing relation thereto and in the direction of movement of stitched articles through the machine.

15 12. A thread severing device for a sewing machine comprising a severing member adapted to be positioned at one side of the path of stitched articles through the machine, a cooperating severing member adapted to be positioned at the opposite side of said path, one of said severing members having a face opposite the other of said

25 severing members, said face having a recess therein, the rear edge of said recess forming a sharp shearing edge with said face, means resiliently urging one of said severing members towards said other severing member, and means for causing the other of said severing members to move across said sharp edge in shearing relation thereto and in the direction of movement of stitched articles through the machine.

30 13. In a sewing machine, a presser foot, a thread severing member carried by said presser foot, a cooperating severing member positioned at the side of the path of stitched articles through the machine opposite said presser foot, the severing member carried by the presser foot having a face opposite said path, said face having a recess therein, the rear edge of said recess forming a sharp shearing edge with said face, and means for causing said cooperating severing member to

35 move across said sharp shearing edge in shearing relation thereto and in the direction of movement of stitched articles through the machine.

40 14. In a sewing machine, a presser foot, a thread severing member carried by said presser foot, a cooperating severing member positioned at the side of the path of stitched articles through the machine opposite said presser foot, the severing member carried by the presser foot having a face opposite said path, said face having a recess therein, the rear edge of said recess forming a sharp shearing edge with said face, and means for causing said cooperating severing member to move across said sharp shearing edge in shearing relation thereto and in the direction of movement of stitched articles through the machine.

45 15. In a sewing machine, a feed dog, a thread severing member positioned at the side of the path of stitched articles through the machine opposite the feed dog, a cooperating severing member carried by the feed dog, said first-mentioned severing member having a face opposite said path, said face having a recess therein, the rear edge of said recess forming a sharp shearing edge with said face, and means for causing said cooperating severing member to move across said sharp shearing edge in shearing relation thereto and in the direction of movement of stitched articles through the machine.

50 16. In a sewing machine, a feed dog, a thread severing member positioned at the side of the path of stitched articles through the machine opposite the feed dog, a cooperating severing member carried by the feed dog, said first-mentioned severing member having a face opposite said path, said face having a recess therein, the rear edge of said recess forming a sharp shearing edge with said face, and means for causing said cooperating severing member to move across said sharp shearing edge in shearing relation ther-

to and in the direction of movement of stitched articles through the machine.

16. In a sewing machine, a feed dog, a thread severing member positioned at the side of the path of stitched articles through the machine opposite the feed dog, a cooperating severing member carried by the feed dog, said first-mentioned severing member having a face opposite said path, said face having a recess therein, the rear edge of said recess forming a sharp shearing edge with said face, means resiliently urging said first-mentioned severing member towards the cooperating severing member carried by the feed dog, and means for causing said cooperating severing member to move across said sharp shearing edge in shearing relation thereto and in the direction of movement of stitched articles through the machine.

17. In a sewing machine, a feed dog, a thread severing member positioned at the side of the path of stitched articles through the machine opposite the feed dog, a transversely-extending tooth on the rear portion of said feed dog having a shearing edge, said severing member having a face opposite said path, said face having a recess therein, the rear edge of said recess forming a sharp shearing edge with the face in which it is formed, means for resiliently urging said severing member towards said tooth of the feed dog, and means for causing the shearing edge of said tooth to move across the shearing edge of said severing member.

18. In a sewing machine, a presser foot, a feed dog, a severing member carried by the presser foot, a cooperating severing member carried by the feed dog, the severing member carried by the presser foot having a face opposite the feed dog, a recess in said face, the rear edge of said recess forming a sharp edge with said face, and means for causing the severing member carried by the feed dog to move across said sharp shearing edge with a shearing action.

19. In a sewing machine, a presser foot, a feed dog, a severing member carried by the presser foot, a cooperating severing member carried by the feed dog, the severing member carried by the presser foot having a face opposite the feed dog, a recess in said face, the rear edge of said recess forming a sharp edge with said face, means resiliently urging the severing member carried by the presser foot towards the severing member carried by the feed dog, and means for causing the severing member carried by the feed dog to move across said sharp shearing edge with a shearing action.

20. In a sewing machine, a presser foot, a feed dog, a thread severing device pivoted at its forward portion to the presser foot, a cooperating severing member carried by the feed dog, the severing member carried by the presser foot having a face opposite the feed dog, a recess in said face, the rear edge of said recess forming a sharp shearing edge with said face, means resiliently urging the severing member carried by the presser foot to a position in which said face is rearwardly inclined downwardly when there is no stitched article between said severing members, and means for causing the severing member carried by the feed dog to move across said sharp shearing edge with a shearing action.

21. A thread severing device for a sewing machine comprising a severing member adapted to be positioned at one side of the path of stitched articles through the machine, a cooperating severing member adapted to be positioned at the op-

posite side of said path, one of said severing members having a face opposite the other of said severing members, said face having a recess therein, said recess being elongated and extending transversely of the path of enchain thread loops attached to a stitched article passing through the machine, the rear edge of said recess forming a sharp shearing edge with said face, and means for causing the other of said severing members to move across said sharp edge in shearing relation thereto and in the direction of movement of stitched articles through the machine.

22. A thread severing device for a sewing machine comprising a severing member adapted to be positioned at one side of the path of stitched articles through the machine, a cooperating severing member adapted to be positioned at the opposite side of said path, one of said severing members having a face opposite the other of said severing members, said face having a recess therein, the bottom of said recess being filled with a relatively soft material, the rear edge of said recess forming a sharp shearing edge with said face, and means for causing the other of said severing members to move across said sharp edge in shearing relation thereto and in the direction of movement of stitched articles through the machine.

23. In a sewing machine, a thread severing device comprising a severing member adapted to be positioned at one side of the path of stitched articles through the machine, a cooperating severing member adapted to be positioned at the opposite side of said path, one of said severing members having a face opposite the other of said severing members, said face having a recess therein, said recess being round and positioned in line with the needle of the sewing machine in the direction of movement of stitched articles through the sewing machine, the rear edge of said recess forming a sharp shearing edge with said face, and means for causing the other of said severing members to move across said sharp edge in shearing relation thereto and in the direction of movement of stitched articles through the machine.

24. A thread severing device for a sewing machine comprising a severing member adapted to be positioned at one side of the path of stitched articles through the machine, a cooperating severing member adapted to be positioned at the opposite side of said path, one of said severing members having a face opposite the other of said severing members, said face having a recess therein, the bottom of said recess being formed by a member of relatively soft material adjustable toward and from said face, the rear edge of said recess forming a sharp shearing edge with said face, and means for causing the other of said severing members to move across said sharp edge in shearing relation thereto and in the direction of movement of stitched articles through the machine.

25. In a thread-chain severing device for sewing machines, a feed-dog having a series of work-engaging teeth terminating in a thread-chain severing member, said thread-chain severing member having a substantially flat face provided with a thread-severing edge at the side of said member remote from said work-engaging teeth.

26. In a thread-chain severing device for sewing machines, a feed-dog having a series of work-engaging teeth terminating in a thread-chain severing member, said thread-chain severing member having a substantially flat work-engag-

ing face disposed at substantially the same level as the work-engaging edges of said work-engaging teeth and being provided with a thread-severing edge at the side of said member remote from said work-engaging teeth.

27. In a thread-chain severing device for sewing machines, a presser-foot having a supporting shank, a work-engaging sole-plate carried by said shank and provided with a needle-aperture, a work-responsive and thread-chain severing member mounted on said presser-foot for movement relative to said sole-plate, said member having a work-engaging face provided with a thread-severing edge disposed rearwardly of said needle-aperture and intersecting a plane normal to and extending lengthwise of the work-engaging face of said sole-plate through said needle-aperture.

28. In a thread-chain severing device for sewing machines, a presser-foot having a supporting shank, a work-engaging sole-plate carried by said shank and provided with a needle-aperture, a work-responsive and thread-chain severing member pivotally attached to the presser-foot shank to extend rearwardly therefrom, said member having a work-engaging face provided with a thread-severing edge disposed rearwardly of said needle-aperture and intersecting a plane normal to and extending lengthwise of the work-engag-

ing face of said sole-plate through said needle-aperture.

29. In a sewing machine, a feed dog, a severing member having a cutting edge positioned at the side of the path of stitched articles through the machine opposite the feed dog, a cooperating severing member carried by the feed dog and provided with a cutting edge, said cooperating severing members being in alignment with the 10 needle of the machine in the direction of travel of stitched articles through the machine, means for moving one of said severing members towards the other when a stitched article is not between them, and means for moving one of said severing members relative to the other in the direction of movement of stitched articles through the machine and in shearing relation to the other severing member.

30. In a sewing machine, including a presser-foot and a feeder unit movable relative to the presser-foot, a thread severing means consisting of a cutting member carried by the presser-foot, and a cutting member carried by the feeder, said cutting members being relatively disposed to engage a thread therebetween and sever the same as such thread is drawn rearwardly by a piece of material passing from beneath the presser-foot.

THOMAS A. ANDERSON.
